UNITED STATES PATENT OFFICE.

ROBERT E. MCKINLEY, OF CARNEGIE, PENNSYLVANIA.

HAIR-CLIPPER.

SPECIFICATION forming part of Letters Patent No. 701,601, dated June 3, 1902.

Application filed October 12, 1901. Serial No. 78,460. (No model.)

To all whom it may concern:

Be it known that I, ROBERT E. MCKINLEY, a citizen of the United States of America, residing at Carnegie, in the county of Allegheny 5 and State of Pennsylvania, have invented certain new and useful Improvements in Hair-Clippers, of which the following is a specification, reference being had therein to the accompanying drawings.

10 This invention relates to certain new and useful improvements in clippers, and is particularly adapted for surgeons' use, the object being to provide a cheap, simple, and effective device of this nature.

15 Briefly described, the invention comprises two handles pivotally secured together, both being broadened into blades at their ends, which are provided with clipping-teeth, the blades being so mounted on the pivot as to 20 permit the detachment therefrom for sharpening of the teeth or other purposes.

25 In describing the invention in detail reference is had to the accompanying drawings, forming a part of this specification, and wherein like numerals of reference indicate corresponding parts throughout the several views, in which—

30 Figure 1 is a detail perspective view of my improved clippers. Fig. 2 is a top plan view thereof, showing the two members moved around at right angles to each other into a position where they may be disengaged. Figs. 3 and 4 show different forms of pivoting means. Fig. 5 is a detail perspective view of the form 35 of pivot shown in connection with Figs. 1 and 2.

35 To put my invention into practice, I provide two plates or blades 1 and 2, the body portion of which is somewhat rectangular in shape 40 and the shanks 3 of which terminate in the handle 4. These blades or plates 1 and 2 are beveled or inclined on their engaging faces, as more clearly shown in Figs. 3 and 4, and are each provided with teeth 5 at their outer 45 ends, the teeth of the upper blade working upon the teeth of the lower blade. The blade or plate 1 is provided with an oblong slot 6 to receive the T-head 7 of the rivet 8, which fastens the two blades or plates together, 50 this rivet being secured in the plate 2 and the head lying across the slots 6, as shown in Fig.

1 of the drawings. In case it is desired to detach the blades or plates from each other, so as to sharpen the teeth or for other purposes, the blade 1 is turned at right angles to the plate 55 2, as shown in Fig. 2, so that the T-head 7 will be brought into alignment with the slot 6. The blade 1 may then be readily removed from the blade 2. In Figs. 3 and 4, while the construction of the plates or blades are 60 the same, I have shown a modified form of pivoting the two plates together, the form shown in Fig. 3 consisting of the rivet 9 and the form in Fig. 4 consisting of a small bolt, which is held by the nut 11. The underneath face of 65 the plate 2 is at a bevel, so as to lie flush upon the flesh and permit the teeth 5 to clip the hair close to the flesh. The peculiar construction of these blades or plates permits the use of such device in instances where the 70 ordinary form of clippers could not be used and enables the clipping of the hair as close to the flesh as may be done with the ordinary clippers.

75 While the construction herein described is the practical form of my invention, yet in the practice of the same it will be observed that various changes may be made in the details of construction without departing from the general spirit of my invention.

80 Having fully described my invention, what I claim as new, and desire to secure by Letters Patent, is—

1. In a device of the character described, a pair of integral substantially rectangular 85 blades having their rear ends extended to form handles, said blades having their inner surfaces contacting throughout and carrying a series of integral clipping-teeth on their forward ends, said blades being pivotally secured 90 near their forward ends, the outer faces of the ends tapering to the cutting-teeth, substantially as described.

2. In hair-clippers, a pair of substantially rectangular integral blades the rear ends of 95 which are extended to form integral handles and which have a series of cutting-teeth formed integral with the front ends thereof, and a pivotal connection between said blades slightly to the rear of said front ends whereby the blades and integral handles may have 100 an opposite lateral movement with relation

to one another and be disengaged when said blades are at a substantial right angle, substantially as described.

3. Hair-clippers which comprise in their entirety a pair of flat blades having integral flat handles carried by their rear ends, with clipping-teeth formed integral with their forward ends, a T-head rivet carried by one of said blades slightly to the rear of the teeth 5 and engaging the outer face of the other of said blades, the last-named blade having an oblong slot formed therein lying transverse

to said head of the rivet whereby said blades may have an opposite lateral movement with relation to one another and may be disengaged when the head registers with the slot, substantially as described. 15

In testimony whereof I affix my signature in the presence of two witnesses.

ROBERT E. MCKINLEY.
